ASSIGNORS TO THE WADE-MONTGOMERY MANUFACTURING COMPANY, OF TAMPA,
FLORIDA, A CORPORATION OF FLORIDA.

EYE-SHADE.

No. 888,945.

Specification of Letters Patent. Patented May 26, 1908.

Application filed November 26, 1907. Serial No. 403,843.

To all whom it may concern:

Be it known that we, BENJAMIN F. WADE and TELEMACHUS F. MONTGOMERY, citizens of the United States, and residents, respectively, of Palmetto, in the county of Manatee, and Tampa, in the county of Hillsboro, State of Florida, have made certain new and useful Improvements in Eye-Shades, of which the following is a specification.

10 This invention is an improvement in eye shades designed especially to protect the eyes against the glare of water, sand and other reflecting surfaces; and the invention consists in certain novel constructions and 15 combinations of parts as will be hereinafter described and claimed.

In the drawing—Figure 1 is a perspective view of the shade applied as in use. Fig. 2 is a top plan view thereof with the side wings 20 turned out to approximately the plane of the main plate. Fig. 3 is a cross section on about line 3—3 of Fig. 2. Fig. 4 is a cross section on about line 4—4 of Fig. 2, and Fig. 5 is a cross section on about line 5—5 of Fig. 2.

25 The device as shown comprises a body or main plate A, which may be beaded or corrugated longitudinally at A' near its front edge to give it the desired stiffness when very thin material is used and this plate A is provided in its rear edge with a notch A² to receive the nose, and whose edge may be rolled or curled as shown at A¹² to increase the comfort in wearing, and is curved or cut out at A³ on opposite sides of the nose notch forming 30 an opening through which the wearer may look down. This cut-away feature at A³ allows the wearer to see where he is going or to observe any obstruction or object below and is of special value to pilots as they can 35 readily see the compass by looking down in rear of the plate A and at the same time have the glare cut off from in front. The feature is also useful for tinners working on a tin roof and for mechanics in other lines. On oppo- 40 site sides of the nose notch A² the main plate A is depressed or concave in its upper side at A⁴, forming seats in which the lower edges of glasses worn by the wearer of the shade may rest.

45 The main plate is provided with sight openings A¹³ in advance of their cut-away portions A³ and preferably in the depressed or concave portions A⁴, and these openings

A¹³ and the cut-away portions A³ are covered by plates of material through which light 55 may pass. This material may be of colored glass or celluloid or other suitable material and may be transparent or translucent or semi-transparent, as may be preferred by the user, and by preference this covering plate A¹⁰ extends throughout the area of the main plate, and when of a suitable green or blue color softens the effect of the shade upon the eyes. This covering plate A¹⁰ may be secured by rivets A¹¹ or any other suitable 60 manner to the main plate and we also prefer to secure lining plates B¹⁰ by means of rivets B¹¹ to the inner faces of the wings B, as will be understood from Figs. 1 and 4 of the drawing.

70 Side wings B are hinged at one edge B' to the main plate A at the ends thereof, so they may be turned out as shown in Fig. 2, or may be turned in flat upon the main plate if desired and these side wings B rest normally in the use of the shade at about a right angle to the plate A and are provided with slots B² and preferably with deflected portions B³ adjacent to the slots B², such slots B² being arranged for the passage of 80 the bows or temples C, which are pivoted at C' to the wings B and extend thence through the slots B² and may be adjusted in the slots B² to position for use and to secure the main plate A at any desired angle, and may also 85 be adjusted in the slots B² to proper position to facilitate the folding of the shade to compact position to fit in the pocket or a case as may be desired. These slots B² also permit any one wearing spectacles to slip the spectacle bows or temples through the slots and 90 adjust the shade plate A under the glasses in an easy and comfortable position. When so used the temples or bows C attached to the wings B may be omitted and the temples of the spectacles serve to secure the shade in place.

95 In practice the shades may be made of aluminum and printed or colored in any suitable dead or flat color, the bows or temples being similar to those ordinarily used on spectacles.

We claim—

1. An eye shade for use below the eyes consisting of a main plate having near its 105 front edge a corrugation or bead extending

from side to side and having in its rear edge a central nose notch and on opposite sides thereof depressions adapted to receive the lower edges of eye-glasses, wings hinged to the main plate at the opposite ends thereof and provided with slots and with deflected portions adjacent thereto and the bows or temples pivoted to the wings and extending through the slots therein, substantially as and for the purposes set forth.

2. An eye shade for use below the eyes comprising a main plate, wings at the ends thereof and arranged in use at approximately a right angle to the main plate and provided with slots elongated in a vertical direction for the passage of temples or bows, and temples or bows pivoted to the wings and movable vertically within said slots.

3. An eye shade for use below the eyes, comprising a main plate conformed at its rear edge to the face below the eyes, and wings hinged to the main plate at the ends thereof and turning upwardly therefrom, and provided with slots for the passage of temples or bows.

4. An eye shade for use below the eyes, comprising a main plate having a nose notch and provided on opposite sides thereof with depressed portions adapted to receive the lower edges of eye-glasses.

5. An eye shade for use below the eyes, comprising a main plate, wings hinged at one edge to the main plate at the ends of the

latter and turning upwardly therefrom and bows or temples pivoted to the wings.

6. An eye shade for use below the eyes, comprising a main plate having a sight opening or openings, and a cover therefor through which light may pass, wings at the ends of said main plate and temples hinged to the wings.

7. An eye shade for use below the eyes comprising a main plate, wings at the ends thereof and provided with slots and with deflected portions adjacent thereto, and temples pivoted to the wings and extending through the slots therein.

8. An eye shade for use below the eyes, comprising a main plate, wings at the ends thereof and when in use at approximately a right angle to the main plate and slotted adjacent to their free edges and temples or bows pivotally connected with the said wings and passed through the slots therein, substantially as set forth.

9. An eye shade for use below the eyes, comprising a main plate having a nose notch and depressed portions on opposite sides thereof, and wings at the ends of said main plate and arranged normally when in use at about a right angle to the main plate.
